UNITED STATES PATENT OFFICE.

SIMON W. FARBER, OF BROOKLYN, NEW YORK.

DESIGN FOR A METAL DISH OR SIMILAR ARTICLE.

Application filed February 16, 1925. Serial No. 12,398. Term of patent 7 years.

To all whom it may concern:

Be it known that I, SIMON W. FARBER, a citizen of the United States of America, residing at Brooklyn, in the county of Kings, city and State of New York, have invented a new, original, and ornamental Design for Metal Dish or Similar Article, of which the following is a specification, reference being had to the accompanying drawing, forming a part thereof.

In the drawing,

Fig. 1 is a side elevation of a dish showing my improved design.

Fig. 2 is a top plan view.

Fig. 3 is an enlarged detail view showing the ornament on the face of the dish.

I claim:

The ornamental design for a metal dish or similar article substantially as shown.

SIMON W. FARBER.
